ELECTROMAGNETIC SWITCH

William E. Stillwell, Jr., Cincinnati, Ohio, assignor
to John B. Pierce Foundation, New York, N. Y.,
a corporation of New York

Continuation of application Serial No. 378,066,
February 8, 1941. This application September
18, 1943, Serial No. 502,924

2 Claims. (Cl. 175—337)

1

This invention relates to electromagnetic switches, and particularly to self-enclosed remotely controlled magnetically operated switches.

An object of the present invention is to provide a self-enclosed low voltage magnetically operated switch which is designed to make and break electrical circuits such as encountered in industrial and household wiring systems.

Another object of the invention is to provide a self-enclosed low voltage remotely controlled magnetically actuated switch for high voltage, having such dimensions as to fit completely within a standard outlet box or standard panel board, in accordance with the permissible standards and specifications of the Underwriters' Laboratories and the National Electric Code.

A further object of the invention is to provide a switch device having the hereinabove described characteristics, and which includes a magnetically operated switch actuator element which is completely responsive to momentary energization.

Still a further object of the invention is to provide a switch device of the type hereinabove described wherein the high voltage circuit making and breaking stroke is rapid and positive in action.

Another object of the invention is to provide a switch having the above characteristics, which includes means for making and breaking the high voltage load circuit in one or more places.

Another object of the invention is to provide a low voltage magnetically operated switch for high voltage load circuits wherein the low voltage magnetic actuator elements are electrically shielded and insulated from the high voltage contact elements, and wherein the device as a whole is electrically and mechanically shielded from harmful external forces and disturbances.

Another object of the invention is to provide improved means for accurately positioning and securing operating elements of the circuit breaker within a housing.

Still a further object of the invention is to provide a circuit breaker having the hereinabove described characteristics which is particularly adapted to be produced by mass production methods, which is durable, dependable in action, and inexpensive.

This application is a continuation of my presently co-pending application Serial No. 378,066, filed February 8, 1941 which subsequently became abandoned, entitled Low voltage remotely controllable magnetically actuated switch.

These and other objects are attained by the

2

means described herein and disclosed in the accompanying drawings, in which:

Fig. 1 is a longitudinal sectional view of a switch manufactured according to the present invention;

Fig. 2 is a section taken on lines 2—2 of Fig. 1;

Fig. 3 is a side elevation, partly in section showing the securement of the switch head to its supporting structure;

Fig. 4 is a sectional view, taken on lines 4—4 of Fig. 1;

Fig. 5 is a plan view of the invention showing one method of installation in a standard electrical outlet box, with the low voltage switch actuator element projecting through one side of the box; Fig. 5 also illustrates schematically a wiring diagram for the controlling circuit.

Fig. 6 is a side elevation of the switch and outlet box of Fig. 5, with the outlet box portion in section; and

Fig. 7 is a plan view of the switch installed wholly within a standard electrical outlet box.

Referring to the drawings the invention comprises a switch 10 and a magnetically operated actuator 11 associated therewith. The switch is adapted for remote control, from any desired plurality of stations S, as diagrammatically shown in Fig. 5. The magnetic circuit of the actuator 11 is preferably wound for low voltage operation, thus placing the wiring from the control stations to the actuator not under the requirements imposed upon high voltage systems by national electrical codes, and making possible substantial savings in weight and complexity of wiring and installation. The main switch contacts (usually high voltage) of switch 10 are entirely electrically isolated from the magnetic actuator 11, and therefore may be designed for any electric service within code requirements of installation.

The switch actuator 11 includes a cylindrical body portion 12, preferably of steel or other magnetic material. A reduced diameter and fits into an aperture provided in an angle plate 14; the housing may be secured to the angle plate 14 by brazing or welding. A forwardly extending leg 15 of the angle plate has a slotted end through which a screw or other fastening means may pass to secure the plate to the base of a standard outlet box as shown in Figs. 5 and 6.

To the angle plate 14 is secured the base 16 of the switch body 10, said base being of insulation material, and carrying the high voltage terminal plates 17 and therewith associated fixed contacts 18 of the main switch circuit. Cooperating with said fixed contacts are movable contacts 20, 20,

carried by an axially movable member 21 of insulation material. A strap 22 carried by said member interconnects the contacts 20, 26 and affords a path of conductivity whereby contacts 20-26 are enabled to bridge-connect fixed contacts 18.

An insulating shim 23 is interposed between the bridging contact organization 20-21-22, the base 16 and the angle plate 14 to insulate the last from the other named parts.

The thereby complete electrical isolation of the respective high and low voltage sections of the switch, and the small size to which the switch may be constructed, makes possible a variation in the manner in which, and in connection with which, the complete device may be installed in a standard electric outlet box. Figs. 5 and 6 show the switch so arranged with respect to an outlet box 24 that the high voltage part of switch 10 is within the box for securement to the base plate thereof or through the base plate to the wall studding, whereas the low voltage switch actuator 11 and all of the low voltage wiring associated therewith is outside of the box. Such an arrangement is advantageous in an installation where the outlet box serves as a junction or several high voltage leads, the connecting and taping of which may take up a large portion of the volume of the box. The housing 12 of switch actuator 11 has an external diameter which permits it to be passed through one of the knock-out openings of the box.

As shown in Fig. 7, the entire switch assembly may be included within the confines of the outlet box if it is desired to protect the switch from plastering or other ceiling or wall finish during the construction of a building in which the system is used.

It is considered to be an important feature of the invention that it may be completely within an outlet box or so disposed with respect thereto that only the high voltage portion of the apparatus is positioned within the box, to maintain the independence in the high and low voltage wiring.

The member 21 is guided in its movement within base 16 by diametrical lateral extensions, see Fig. 4. Said member is secured to an end of a brass shaft 26, by means affording self-adjustability of the member, so that the movable and fixed contacts will engage despite slight irregularities in the positioning thereof.

To the opposite end of the shaft 26 there is secured an overthrow spring or snap-acting member 27 held with its periphery in engagement with a sloping shoulder 28 of the housing 12. Said spring is desirably as described and claimed in my co-pending application Serial No. 441,382, filed May 1, 1942, which subsequently became abandoned, for Toggle springs.

The shaft 26 is guided in its longitudinal movement by passage through the aligned bores of two end stops or cores 30 and 31, which receive the sliding shaft. The end stops are of steel or other magnetic material and are suitably positioned within the housing 12; it will be noted that a shouldered end of stop 30 rests against an inner end wall of housing 12, and that the flanged head of end stop 31 abuts a shoulder 32 provided within housing 12.

Disposed about the end stop 30 is a solenoid coil 33, and about end stop 31 is a solenoid coil 34; when the coils are energized selectively through the wiring circuit (shown in dotted lines) the respective end stop of the energized

coil forms a pole of the magnetic system thereby created. Between said coils is disposed a metal annular member 35, being in engagement with the iron or steel housing 12, and positioned in the housing in engagement with a shoulder 36 formed therein. Said annular member 35 serves also to position the solenoid spools by the interfitting of shoulders 37 thereon into a groove on the respective sides of the annular member.

Secured to the shaft 26 is a magnetically responsive armature 38 having an outside diameter slightly less than the inner diameter of the annular member 35 to avoid a frictional contact of the armature and the core. It will be noted that the ends of the armature are conical, corresponding to the conical depressions of the respective end stops 30 and 31.

The magnetic flux created by the respective energized solenoids passes through and is confined within the high permeability structure comprising the housing 12, the core members 30 (31), the annular member 35, and the armature 38, all of which are preferably of metals having high magnetic permeability. This construction assures a powerful pull on the armature 38 to insure immediate and strong response to the control circuit.

If desired, the positioning of the end stops within the housing is such that the permitted travel of the shaft 26 in either direction is less than the total extent of throw of the toggle spring 27 from one to the other of its positions of stability. In Fig. 1, showing the switch in open circuit position, the armature 38 has abutted against the end stop 31 before the spring 27 has completed its full throw, whereupon said spring yieldingly holds the armature in engagement with the end stop. This is advantageous in avoiding hum when the magnetic actuator 11 is employed with alternating current. Likewise the engagement of the armature 38 with end stop 30 occurs before the spring has fully thrown to its other position of equilibrium so that said spring exerts a continuous pressure in the given direction. It will be understood that prior to the engagement of the armature with the end stop 30, the movable and fixed contacts of the switch 11 have come into engagement.

The precise relationship of the travel of shaft 26 and the position of end stops 30 and 31 is established by means of the respective shoulders of the housing 12, as previously described.

To maintain the annular member 35 and the end stop 31 in engagement with the respective shoulders of the housing 12, and also accurately to position the spring 27, there is employed an insulating end cap or spider 40 formed with a rim 41 and a plurality of spaced legs 42, the latter straddling the spoked portions of the spring 27 as shown in Fig. 2. The ends of the legs 42 rest upon the surface of the end stop 31 and hold the end stop in position against the shoulder 32, and, through the intervening solenoid 33, holds annular member 35 against the shoulder 36. The spring 27 is confined by means of a washer 43, against the rim 41 of the spider 40. The spider 40 therefore serves as means to maintain the various operating elements of the switch in proper relationship one with the other.

To confine the spider 40 in its position, there may be employed a metallic cap 44, the rim of which rests upon the cap 40, and is held in position by beading or flanging an end of the housing 12 about the circumference of the cap, as shown in Fig. 1.

The solenoid spools, the annular member, and

end stop 31 are suitably slotted to accommodate the wiring from the solenoids 33 and 34; passages 45 through the leg portions of spider 40 are channels through which the wires may be run.

Whereas I have described my invention by reference to specific forms thereof, it will be understood that many changes and modifications may be made provided they do not depart from the scope of the claims.

I claim:

1. Electromagnetic means, comprising a magnetic shell formed with a plurality of concentric bores of successively smaller diameters, the line of demarcation between successive bores being of the nature of angular shoulders, magnetic end stop means and an intermediate magnetic annular member positioned within said shell by engagement with said shoulders, an armature slidably positioned within said annular member for operation between said end stops, a snap spring operatively associated with said armature, and cap means disposed within said shell and bearing against said snap spring and said end stop means to maintain the positioning thereof within said shell.

2. Switch actuator means, comprising a tubular casing, electromagnetic core means disposed within said casing, an armature mounted for reciprocal movement between said electromagnetic core means, a snap spring having a rim portion supported peripherally by said casing and a spoked center portion operatively associated with said armature for maintaining the armature resiliently at either of its extremes of reciprocal movement, cap means having a rim engageable with the rim of said snap spring to maintain the support thereof by said casing and leg means

straddling the spoked portion of said snap spring and engageable with said electromagnetic core means to maintain the positioning thereof within the casing, and means for securing the cap means within said casing.
